US0D1033212S

(12) **United States Design Patent** (10) Patent No.: **US D1,033,212 S**
(45) Date of Patent: ** Jul. 2, 2024

(54) **REINFORCING BAR COUPLER**

(71) Applicants: **Seoul National University R&DB Foundation**, Seoul (KR); **EURO Engineering Co., Ltd.**, Seoul (KR)

(72) Inventors: **Thomas Hyun Koo Kang**, Seoul (KR); **Keun Sam Kim**, Seoul (KR)

(73) Assignees: **Seoul National University R&DB Foundation**, Seoul (KR); **EURO Engineering Co., Ltd.**, Seoul (KR)

(**) Term: **15 Years**

(21) Appl. No.: **29/737,663**

(22) Filed: **Jun. 11, 2020**

(51) LOC (14) Cl. **08-08**

(52) U.S. Cl. **D8/382**

(58) **Field of Classification Search**

(57) **CLAIM**

The ornamental design for a reinforcing bar coupler, as shown and described.

DESCRIPTION

FIG. 1 is a front perspective view of a reinforcing bar coupler showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a bottom perspective view thereof.

The broken lines in the drawings illustrate portions of the reinforcing bar coupler and form no part of the claimed design.

1 Claim, 8 Drawing Sheets
